PAPER HANGER'S PLUMB BOB

John H. Mehaffey, Metuchen, N. J.

Application September 9, 1949, Serial No. 114,874

3 Claims. (Cl. 33—210)

1

This invention relates to a paper hanger's plumb bob, the primary object of the invention being to provide a device for accurately marking walls and other vertical supports to provide true verticals and horizontals as guides for hanging paper and for checking work already done, as for exactly matching wallpaper designs.

Another important object of the invention is to provide a device of the above-indicated character which lies flat against a wall or other vertical support and which eliminates drag or friction between the bob and the vertical surface as a detrimental factor in the accurate use and operation of the device.

Other important objects and advantageous features of the invention will be apparent from the following description and the accompanying drawings, wherein, merely for purposes of illustration, a specific embodiment of the invention is set forth in detail.

In the drawings:

Figure 1 is an outboard side elevation;

Figure 2 is a transverse vertical section, taken on the line 2—2 of Figure 1;

Figure 3 is an enlarged fragmentary vertical section, taken on the line 3—3 of Figure 2;

Figure 4 is a horizontal section, taken on the line 4—4 of Figure 3;

Figure 5 is a fragmentary outboard side elevation showing the lower part of a modified form, embodying anti-friction balls;

Figure 6 is a transverse vertical section, taken on the line 6—6 of Figure 5.

Referring in detail to the drawings, wherein similar numerals designate like parts throughout the several views, the numeral 7 generally designates the body of the bob, having a substantially isosceles open triangular shape, having plane parallel inboard and outboard sides 8 and 9, respectively. The body 7 includes the horizontal base 10 having a straight plane under surface 11 extending to intersect the outboard and inboard sides 8 and 9, so as to define horizontal corners 12 and 13, respectively.

Between the points 14 and 15, equidistantly spaced from the ends of the base 10, the upper side of the base is angularly reduced to provide the surface 16 which declines in an outboard direction from intersection at 17 with the inboard bob side 8 to intersection with the outboard corner 13. At the middle or center of the elevated inboard edge 17 of the surface 16 is formed a notch 18 which is used to mark a vertical on a wall against which the device is engaged.

From the ends of the base 10 rise the converg-

2

ing uprights or laterals 19, 19 which meet at their upper ends in an apex 20 having a flat top 21 formed centrally with a threaded recess 22, in which is threaded a clamping ring 23. As shown in Figures 2 and 4, the recess 22 is displaced somewhat toward the inboard side 8 of the plumb bob body 7 for a purpose hereinafter explained.

Held in place in the recess 22 by the ring 23 is the flat disc base 24 of the vertical cord-attaching element 25 to which the plumb bob cord 26 is adapted to be secured. The disc 24 is smaller in diameter than the recess 22 so that the base 24 can be shifted in the recess into perpendicular alignment with the notch 18 and then clamped in place by the ring 23.

The base 10 is traversed midway between its edges 12 and 13 by two vertical parallel screws 27, 27 which are equidistantly spaced from the points 14 and 15 and have heads 28 countersunk flush with the under surface 11 of the base

10. The shanks of the screws 27, 27 rise above the base to rigidly support thereon the horizontal bubble level 29 which involves a U-shaped bracket 30 traversed by the screws 27, 27. Upper and lower nuts 31 and 32, respectively, on the screws engage the top and bottom of the bight of the U-shaped bracket 30 and afford means whereby the level 29 can be adjusted to parallelism with the base 10.

When the above-described device is suspended by the cord 26, the cord-attaching element 25 having been adjusted to vertical alignment with the marking notch 18, and hence with the bubble 33 of the level 29, the inboard displacement of the cord 26 provided for by the structure described above, causes the body 7 to engage the inboard base edge 12 against the wall 34 with the body 7 leaning slightly away from the perpendicular and hence away from the wall, thereby eliminating undesirable drag of the body 7 upon the wall, whereby an accurate plumb position of the device is assured. Hence, a mark made in the notch 18 will be perpendicular with the point above the plumb bob body 7 from which the cord 16 is suspended. It will be apparent that the cord may be attached to a nail or other supporting element fastened to a wall, or the cord may be held in the hand.

If desired, the lower part of the body 7 may be provided with wall-drag and friction-reducing balls 35, 35 preferably larger in diameter than the thickness of the body, and arranged to project equally at the inboard and outboard sides 8 and 9, respectively, of the body 7, as shown in Figures 5 and 6. To accommodate the balls 35,

35, the lower ends of the laterals 19 are formed at their lower ends with circular threaded recesses 36 opening through one side thereof, the floors of the recesses being formed with spherical segmental portions 37 fitting the balls and opening through the opposite side of the laterals, as shown in Figure 6. The balls 35 fit in the recess portions and are held revolubly in place by threaded rings 38 having spherical segmental openings 39 fitting the balls.

It will be observed that with the device properly adjusted, the bubble 33 of the level 29, when aligned with the notch 18, assures marking of an accurate vertical on the wall 34 through the notch 18, with the bubble 33 at center position. In this level position of the device, the straight under surface 11 of the base 10 serves to establish an accurate guide for marking a true horizontal on the wall 34.

I claim:

1. A paper hanger's plumb bob comprising a plumb bob body comprising a horizontally-elongated base and laterals rising from the opposite ends of said base, an apex joining the upper ends of said laterals, an element on said apex for suspending said body relative to a vertical wall, a level mounted on said body above and parallel to said base and having a bubble indicator, said base being formed with a central notch for marking a perpendicular vertical on the wall when said body is positioned with said notch aligned with the bubble indicator of said level, said apex being formed with a threaded recess opening through its top having a clamping ring threaded therein, said element comprising a vertical member rising through said ring to which a cord is attachable, a disc base on the lower end of said member smaller in diameter than and engaging the bottom of said recess and movable edgewise in all directions in said recess to perpendicularly align said member with said notch, said ring being arranged to be screwed down upon said base to hold said element in adjusted position.

2. A plumb bob comprising a horizontally disposed base, a pair of spaced uprights rising from said base, a U-shaped bracket positioned within the space between said uprights above and spaced from said base with its legs facing toward the free ends of said uprights, a horizontally disposed level provided with a bubble indicator in-

termidate its ends supported in the legs of said bracket, securing means extending through the bight of said bracket and engaging said base for securing said bracket to said base, and means connected to the free ends of said uprights for suspendingly supporting said uprights from a supporting element, said base being provided with a notch substantially centrally thereof for marking a perpendicular vertical on a vertical wall when said base is in horizontal position as indicated by the bubble indicator.

3. A plumb bob comprising a horizontally disposed base, a pair of spaced uprights rising from said base, a U-shaped bracket positioned within the space between said uprights above and spaced from said base with its legs facing toward the free ends of said uprights, a horizontally disposed level provided with a bubble indicator intermediate its ends supported in the legs of said bracket, securing means extending through the bight of said bracket and engaging said base for securing said bracket to said base, means connected to the free ends of said uprights for suspendingly supporting said uprights from a supporting element, said base being provided with a notch substantially centrally thereof for marking a perpendicular vertical on a vertical wall when said base is in horizontal position as indicated by the bubble indicator, and anti-friction means on the lower part of the inboard side of said plumb bob for establishing non-drag engagement of the lower part of said body with a wall to be marked through said notch.

JOHN H. MEHAFFEY.
